COMBINED TOOTHBRUSH, TOOTHPASTE TUBE AND SOAP BAR HOLDER

Astor M. Antaramian, 3133 E. Mono,
Fresno, Calif. 93702

Filed Oct. 23, 1968, Ser. No. 14,150

Term of patent 14 years

Int. Cl. D6—01

U.S. Cl. D33—26

FIG. 1.

FIG. 2.

FIG. 3.

FIG. 4.

FIG. 5.

FIG. 6.

FIG. 1 is a perspective view of a combined toothbrush, toothpaste tube and soap bar holder showing my new design.

FIG. 2 is a side elevation thereof with the opposite side being identical to the side shown.

FIG. 3 is a front elevation thereof.

FIG. 4 is a rear elevation thereof.

FIG. 5 is a top plan view thereof.

FIG. 6 is a bottom plan view thereof.

The broken line representations of a plurality of toothbrushes, a toothpaste tube and a plurality of bars of soap in FIGS. 1 and 2 are for purposes of illustration only.

I claim:

The combined toothbrush, toothpaste tube and soap bar holder, of my new design essentially as shown and described.
